UNITED STATES PATENT OFFICE.

EDWIN C. RIEGEL, OF NEW YORK, N. Y.

DESIGN FOR A CANE.

49,909.

Specification for Design. Patented Nov. 14, 1916.

Application filed January 20, 1916. Serial No. 73,259. Term of patent 3½ years.

To all whom it may concern:

Be it known that I, EDWIN C. RIEGEL, a citizen of the United States, residing in the city of New York, borough of Manhattan, in the county and State of New York, have invented a new, original, and ornamental Design for a Cane, of which the following is a specification, reference being had to the accompanying drawing, forming part thereof.

The figure is a perspective view of a cane, showing my new design.

The skeleton handle No. 1 of the cane has an oval form, the broader portion being up-

permost, and the sides curving therefrom inward toward each other, thus forming the symmetrical crotch 2, whence the straight, smooth, and tapered stock of body 3 extends downward.

I claim:

The ornamental design for a cane, as shown and described.

EDWIN C. RIEGEL.
